C. L. CROFT.

CATCH FOR STANDS FOR MOTORCYCLES AND THE LIKE.

APPLICATION FILED JAN. 26, 1920.

1,393,508.

Patented Oct. 11, 1921.

Charles Leighton Croft,
Inventor
by Frank P. Meentemore
his Attorney.

500,000
UNITED STATES PATENT OFFICE.

CHARLES LEIGHTON CROFT, OF BALHAM, LONDON, ENGLAND, ASSIGNOR OF ONE-HALF TO DAVID STOTT COOPER, OF LONDON, ENGLAND.

CATCH FOR STANDS FOR MOTORCYCLES AND THE LIKE.

1,393,508.

Specification of Letters Patent.

Patented Oct. 11, 1921.

Application filed January 26, 1920. Serial No. 354,132.

To all whom it may concern:

Be it known that I, CHARLES LEIGHTON CROFT, a subject of the King of Great Britain and Ireland, residing at 21, Ritherdon road, Balham, London, England, have invented new and useful Improvements in Catches for Stands for Motorcycles and the like, of which the following is a specification.

10 My invention relates to an improvement in the construction of catches on the mud guards of motor cycles and the like, for holding in position the stand, the object being to devise a simple catch, capable of a quick and easy method of attaching and detaching the stand and locking same to prevent the danger of it dropping down when the motor cycle is running on the road.

15 The accompanying drawings illustrate a catch embodying my improvements.

Figure 1 is a side elevation.

Fig. 2 is a back elevation.

20 Fig. 3 is a detail drawing illustrating the attachment of the catch to the mudguard; and the stand locked up in position.

25 The catch is bolted to the mudguard in the ordinary manner and consists of a piece of metal A with forked ends B, B¹ and splayed out for the reception of the back rod C of the stand D. The outer member B¹ of the fork is slotted out, into which freely fits the arm E formed of a flat piece of metal which is hinged to the lower end of B¹ at F. The inner vertical side of the arm is at an angle to the vertical forming an inclined surface P the top edge of which abuts against the inner side of the fork. The top side of the arm E upon which rests the rod C of the stand is cam shaped. An elongation outward of the upper portion of the catch forms a trigger T for releasing the stand, a spring S is attached to the trigger and locks the catch.

30 In the top end of the fork is a small spring U which takes up any play between the stand and the catch, preventing any rattle.

The action of the catch is as follows:

35 The stand is forced up the fork B B¹, and by means of the incline surface, the arm E

is forced back, until the stand passes above the top of the arm, when the arm falls back and locks the stand in position, upon depressing the trigger T the stand is released and falls down.

55

I claim:

1. In a catch for motor cycle stands, the combination of a fork-shaped fitting to receive the end of the motor cycle stand, an arm pivotally mounted at its lower end in a centrally disposed slot in one leg of said fitting, said arm having its lower inner side normally inclined to the vertical and forming an inclined surface and its upper inner side of cam shape, said arm projecting rearwardly from said slot and terminating in a trigger for the purpose of operating the arm and also for the attachment of one end of a spring for locking said arm in functioning position, for the purposes described.

2. In a catch for motor cycle stands, the combination of a fork-shaped fitting to receive the end of the motor cycle stand, an arm pivotally mounted at its lower end in a centrally disposed slot in one leg of the said fitting, said arm having its lower inner side normally inclined to the vertical and forming an inclined surface and its upper inner side of cam shape, said arm projecting rearwardly from said slot and terminating in a trigger for the purposes of operating the arm and also for the attachment of one end of a spring for locking said arm in functioning position, and resilient buffering means located between the legs of said fork-shaped projection coöoperating with the end of said stand, for the purposes described.

3. In a catch for motor cycle stands, the combination of a fork-shaped fitting adapted to be fitted to a mudguard of a motor cycle, and shaped to receive the end of the stand therefor, an arm pivotally mounted in a vertical slot in the outer leg of said fitting, said arm comprising a flat plate pivoted at its lower end in said slot and having its lower inner face normally inclined to the vertical and forming an inclined surface and its upper inner face lo-

cated above the point of connection to the outer leg of said fitting, said arm extending rearwardly to form a trigger for the purpose of operating the same, a spring connected at one end to said fitting and at the opposite end to said trigger, and a spring located between the legs of the fitting ar-

ranged to engage the end of the stand to prevent rattling, for the purpose described.

CHARLES LEIGHTON CROFT.

Witnesses:

CHARLES J. CROFT,
AVIS HUGHES.
